INVENTOR.

BY
Geo. P. Kimmel.
ATTORNEY.

UNITED STATES PATENT OFFICE.

JOSIAH H. COLLINS, OF BEGGS, OKLAHOMA.

RAILWAY RAIL FASTENER.

1,411,163.

Specification of Letters Patent. Patented Mar. 28, 1922.

Application filed November 14, 1921. Serial No. 515,025.

To all whom it may concern:

Be it known that I, JOSIAH H. COLLINS, a citizen of the United States, residing at Beggs, in the county of Okmulgee and State 5 of Oklahoma, have invented certain new and useful Improvements in Railway Rail Fasteners, of which the following is a specification.

This invention relates to railway rail fasteners, and has for one of its objects to improve the construction and increase the efficiency and utility of devices of this character.

Another object of this invention is to provide a device of this character which may 15 be applied to rails of various sizes and forms without change in the rail structure.

With these and other objects in view the invention consists in certain novel features of construction as hereinafter shown and described and then specifically pointed out in the claims, and in the drawings illustrative of the preferred embodiment of the invention;—

Figure 1 is a perspective view of the improved device applied.

Fig. 2 is a plan view, partly in section.

Fig. 3 is a side elevation.

Fig. 4 is an end elevation of the improved device applied to a railway rail, the rail 30 being in transverse section.

Fig. 5 is a transverse section on the line 5—5 of Fig. 3.

Fig. 6 is a detached perspective view of one of the clamp bolts.

Fig. 7 is a detail perspective view of a part of the wedge key and the holding pawl.

The improved device comprises a clamp plate 10, preferably tapered or wedge shaped longitudinally, and of substantially the same 40 length as the ordinary "fish" or clamp plate. The plate 10 bears against the web portions of the rails, represented conventionally at 11 and 12, and is apertured to receive holding pins or bolts 13, the latter spaced at the 45 usual distances, and extending through the apertures for the usual clamp bolts.

The ordinary bolt apertures through the rail webs are thus utilized to receive the bolts 13, a clamp plate 14 being employed at the 50 sides of the webs opposite to the plate 10, and against which the heads 15 of the bolts bear.

At its thicker end the clamp plate 10 is formed with a guideway or housing 16.

Each of the pins or bolts 13 is provided 55 with a transverse slot 17, and engaging

through these slots is a wedge key 18, the thinner end of the key passing through the housing or guideway 16, as shown. At its smaller end the key 18 is provided with a 60 plurality of recesses or notches 19 and likewise with a plurality of apertures 20 in spaced relation. Pivoted at 21 within the guideway 16 is a pawl device 22 adapted to engage the recesses or notches 19 in the 65 wedge key and operating to lock the latter in adjusted position.

The pawl member is provided with an outstanding pin 23 extending through a slot 24 in the housing and surrounded by a spring 25 70 to maintain the pawl yieldably pressed against the wedge key and in one of the notches.

The housing 16 is likewise provided with apertures to receive a cotter pin 26 which 75 passes through one of the apertures 20 in the wedge key and thus operates as an additional holding means to the wedge key.

By this means a simply constructed fastening device is provided which firmly locks 80 the adjacent ends of the rails together and prevents them from working loose under the severe strains to which they will be subjected by the rolling stock, and containing no loose parts to become detached by this 85 jarring and concussion.

The preferred embodiment of the invention is disclosed in the drawings and set forth in the specification, but it will be understood that modifications within the scope 90 of the claimed invention may be made in the construction without departing from the principle of the invention or sacrificing any of its advantages.

Having thus described the invention, what 95 is claimed as new is:—

1. A railway rail fastening comprising a wedge shaped clamp plate adapted to bear against the webs of a pair of rails at their confronting ends and provided with a guideway at one end, said clamp plate having a plurality of apertures, clamp bolts extending respectively through the rail webs and likewise through the apertures of the clamp plate, and each bolt being provided with 100 a transverse slot, a wedge key extending through the slots of the bolts and through the guideway of the clamp plate, and means for locking said wedge key from movement longitudinally.

2. In a device of the class described, abutting members, a clamp plate adapted to bear 110

against one of said abutting members and having a housing at one end, said clamp plate and the abutting members having a plurality of registering apertures, clamp bolts 5 extending respectively through said registering apertures, and each bolt being provided with a transverse slot, a wedge key extending through the slots of the bolts and through the guideway of the clamp plate 10 and provided with spaced recesses, and a spring controlled pawl device within said guideway and engageable with said recesses.

3. A device of the class described comprising a wedge shaped clamp plate adapted to

bear against a bearing member and provided with a guideway at one end, said clamp plate having a plurality of apertures, clamp bolts extending respectively through the bearing member and likewise through the apertures of the clamp plate, and each bolt 20 being provided with a transverse slot, a wedge key extending through the slots of the bolts and through the guideway of the clamp plate, and means for locking said wedge key from movement longitudinally. 25

In testimony whereof, I affix my signature hereto.

JOSIAH H. COLLINS.
